PISTON AND FIRE RING CONSTRUCTION
Donald M. Hesling, Laverne W. Kibbey, and Lewis M. Davis, Muskegon, Mich., assignors to Sealed Power Corporation, Muskegon, Mich., a corporation of Michigan

Filed Jan. 29, 1962, Ser. No. 169,514
5 Claims. (Cl. 277—193)

This invention relates to a piston and fire ring construction for use in internal combustion engines, particularly diesel engines.

Sticking of the top compression ring and bore scuffing have been problems in diesel engines, particularly in engines which have been modified, run at higher speeds or turbocharged in order to increase the horsepower output of the engines.

The piston configuration and piston ring arrangement normally used in these heavy duty engines is such that the top compression ring is placed a considerable distance from the top surface of the piston, leaving an unusually wide head land. This is especially true in open chamber type diesels where part or all of the combustion chamber is in the head of the piston. The large mass of metal in the head land in the top ring groove area becomes very hot since it is exposed to the flame of the combustion process. However, fuel and lubricating oil are only partially burned in this area and consequently a hard deposit forms. Bore scuffing can result when the deposit on the head land becomes sufficiently thick to take up the normal clearance provided between the land and the cylinder wall. Scuffing can also occur when carbon deposits from partially-burned fuel and lubricating oil fill up the normal clearance between the inside diameter of the top compression ring and the root diameter of the piston groove, or between the side of the ring and the side of the groove. In both of the latter cases, when the ring operating clearances are taken up the outside diameter of the ring is permanently exposed beyond the piston lands. Therefore, when the piston rocks slightly during its normal operation, a very high pressure condition will exist between the ring face and the cylinder bore and hence scuffing will result.

An object of the present invention is to provide an improved piston and fire ring assembly for protecting the head land of the piston as well as the top compression ring thereof located at the conventional position on the piston.

Another object is to provide an improved fire ring and piston assembly operative to shield or baffle the area below the fire ring from the flame front without becoming clogged by carbon deposits in the fire ring groove.

A further object is to provide an improved piston and fire ring assembly operative to keep the cylinder wall scraped free of deposits that might otherwise work their way into the compression ring grooves located below the fire ring groove.

In the accompanying drawing:

FIG. 1 is a fragmentary vertical section of a piston and ring assembly in a cylinder with the piston and ring assembly constructed in accordance with the present invention.

FIG. 2 is a plan view of a fire ring segment of the present invention.

FIG. 3 is a fragmentary enlarged view of a portion of FIG. 1 illustrating two fire ring segments assembled in the fire ring groove of the piston in accordance with the present invention.

FIG. 4 is a fragmentary sectional view corresponding to that of FIG. 3 but reduced in scale therefrom, illustrating a modified piston groove construction for aluminum pistons provided with the present invention.

FIG. 5 is a fragmentary sectional view similar to that of FIG. 4 illustrating a still further modified piston groove construction.

2

FIGS. 6 and 7 are fragmentary sectional views similar to that of FIG. 3 but enlarged thereover to illustrate the operation of the piston and fire ring assembly of FIG. 3.

Referring to FIG. 1, the piston and fire ring construction of the present invention is shown applied to a conventional heavy duty piston 10 mounted for reciprocation in a cylinder 12 of a conventional diesel engine, not otherwise shown. Piston 10 is provided with suitable circumferential ring grooves 14, 16 and 18 for respectively receiving conventional top and middle compression rings 20 and 22 and a conventional oil ring 24. Piston 10 is designed for open chamber type diesel engines and hence a large recess 26 is provided in the head of the piston to form part or all of the combustion chamber. As a result the top compression ring 20 is placed a considerable distance from the top surface 28 of the piston, leaving an unusually wide head land 30 indicated by the bracket in FIG. 1.

In accordance with the present invention, a circumferential ring groove 32 is provided in head land 30 which preferably is located as close as possible to the top end surface 28 of piston 10 consistent with the strength of the land material disposed between groove 32 and top surface 28. An improved fire ring assembly 34 is inserted in groove 32 which preferably comprises two steel segments 36 and 38 as more clearly shown in FIG. 3.

Fire ring segments 36 and 38 are identical and each comprise an annular ring (FIG. 2) with a parting gap 39 and an outer peripheral cylinder scraping surface 40 which may be either plain, chrome plated, or coated or plated with some other wear resistant substance. The fire ring segments may be made in a conventional manner by coiling up suitable steel stock into the circular ring configuration of FIG. 2, heat treating the ring to 800° F. to relieve coiling stress and, if desired, plating the outer periphery of the ring to provide the scraping surface 40 and then reheating to relieve plating stress. While two fire ring segments 36, 38 are preferred, fire ring assembly 34 may comprise a multiplicity of such segments or only one of such segments.

One critical feature of the piston and fire ring assembly of the present invention resides in the dimensional relationship of the fire ring assembly 34 relative to the fire ring groove 32 and to the diameter of the bore of cylinder 12. The total axial width of the two fire ring segments 36, 38, i.e., the dimension of the segments which is parallel to the axis of the piston, is considerably less than the corresponding axial width of fire ring groove 32. This provides a relatively great amount of side or axial clearance, such as that shown in FIG. 3 between the top surface 41 of fire ring segment 36 and the top wall 42 of groove 32, as compared to the axial clearance normally specified for a conventional compression ring (usually .002-.004 inch). The width of groove 32 is the distance between top wall 42 and bottom wall 44 of groove 32. It has been found that the best results are obtained when the two fire rings 36, 38 are axially dimensioned to provide a total axial clearance ranging from .003 to .012 inch. The preferred range is from .003 to .006 inch. The other important dimensional characteristic of fire ring segments 36, 38 is their outside and inside diameters in the free or expanded condition thereof, the outside diameter being substantially the same as the inside diameter of the bore of cylinder 12 so that these segments when installed in piston 10 within cylinder 12 exert little or no radial force against the cylinder wall. The inside diameter of fire ring segments 36, 38 is greater than the root diameter of piston groove 32 so that the segments do not contact or bottom against the back wall 43 of the groove during normal operation of the engine.

It will thus be seen that the fire ring assembly 34 has what normally would be thought of as a "sloppy"

fit in piston groove 32. However, in accordance with the present invention fire ring assembly 34 is not intended to provide a 100 percent seal as is expected from a compression ring. Rather, the purpose of these fire rings is to "baffle" or "shield" the area below them from the flame front and also to keep the cylinder wall scraped free of deposits that might otherwise work their way into compression ring grooves 14 and 16.

The operation of fire ring segments 36 and 38 is best shown in FIGS. 6 and 7. Due to the axial clearance in the ring groove and the lack of radial pressure against the wall of cylinder 12, the fire ring segments 36 and 38 can rotate and shift axially in groove 32 relative to piston 10. This movement is induced by reciprocation of the piston in the cylinder and results in a cleaning action between the top and bottom walls 42 and 44 of groove 32 and the respectively adjacent surfaces of fire ring segments 36 and 38. Since the fire ring segments do not completely seal compression, no great pressure is built up behind the segments and they are not forced out against the cylinder wall with extreme pressures. Preferably, the fire ring segments 36, 38 have a high radial thickness to axial width ratio, such as about six to one, as compared to the usual ratio of about two and one quarter to one for conventional compression rings, and are relatively lightweight. This tends to reduce ring groove pounding due to inertial forces.

Due to their relatively sloppy fit in groove 32, fire ring segments 36 and 38 have room in the groove to "dish" (movement of the ring segment from a planar to a conical shape) between the inclined positions illustrated in solid lines respectively in FIGS. 6 and 7. The dishing movement results from the net combined effect of gas pressure, inertial and momentum forces and friction between the first ring segments 36, 38 and the wall of the cylinder during reciprocation of the piston. For example, on the intake stroke of a four-cycle engine the ring segments 36, 38 assume the upwardly dished position of FIG. 6. The downwardly dished position shown in solid lines in FIG. 7 is a transient condition at the beginning of the compression stroke. During the remainder of the compression stroke, the combustion stroke and the exhaust stroke the ring segments 36, 38 lie flat against the bottom side 44 of groove 32 as indicated in broken lines in FIG. 7. This dishing movement produces what may be termed a "windshield wiper" action between the fire ring segments 36, 38 and the wall of cylinder 12 which assists in sweeping the cylinder wall clean. The dishing movement also causes the mutually adjacent surfaces of fire ring segments 36, 38 to move radially relative to one another, thereby assisting in keeping fire ring assembly 34 clean so that the fire segments 36, 38 thereof remain free to move radially independently of one another to insure maximum contact of each fire ring scraping surface 40 with the wall of cylinder 12.

When it is desired to install a fire ring assembly in accordance with the present invention in a piston made of aluminum, or some other relatively soft material, it is preferred to use the modified piston groove construction illustrated in FIGS. 4 and 5. In FIG. 4 an aluminum piston 50 is partially shown which generally corresponds to piston 10 in configuration and in the location of top compression ring 20 and a groove 14 therefor. However, instead of casting or machining a fire ring groove directly in the material of the piston, an annular cast iron insert 54 is placed in the piston mold and the molten aluminum is poured around the insert. A fire ring groove 56 is then machined in the cast iron insert 54 to receive fire ring assembly 34, it being understood that the dimensional relationship between the fire ring assembly, insert groove 56 and the bore of cylinder 12 is as specified in the previously described embodiment. Alternatively, as shown in FIG. 5, the aluminum piston 50 may be cast with an even larger cast iron insert 60 therein which encompasses the location of the compression ring 20 as

well as fire ring assembly 34. Both a fire ring groove 62 and a compression ring groove 64 are then machined in insert 60 to respectively receive fire ring assembly 34 and top compression ring 20, again observing the dimensional relationships disclosed herein. In this manner the relatively soft aluminum or other material of piston 50 may be isolated from the wearing effect of the windshield wiper action of fire ring assembly 34.

It is to be understood that the aforementioned range of axial clearances between fire ring assembly 34 and groove 32 are intended to apply to a range of piston sizes currently employed in known diesel engines of the heavy duty type. Also, the lower limit of the aforementioned axial clearance range is more critical than the upper limit. If less than the specified minimum clearance is provided, ring sticking will be found to occur as in prior art fire ring construction. If more clearance is provided than that specified for the upper limit of said range, the fire ring assembly would still be operable to serve as a baffle to shield the compression rings therebelow from the flame front and thereby reduce sticking, but the excessive sloppiness of such a fit would cause hammering of the fire assembly in the fire ring groove and result in excessive wear of the ring groove.

By way of example and not by way of limitation, a piston and fire ring construction operable in accordance with the invention may be constructed according to the following specifications:

Maximum individual axial width of fire ring segments 36, 38 as installed	.0310 inch.
Axial width of groove 32	.68-0.69 inch.
Cylinder bore diameter	About 4.000 to 5.125 in.
Free outside diameter of fire ring segments 36, 38	Substantially equal to cylinder bore diameter.
Individual radial thickness of fire ring segments 36, 38	.167-.173 inch after plating.
Clearance between inside diameter of ring 24 and root diameter of piston groove 32	.032-.042 inch.
Distance across gap 39 at free O.D. of fire ring segments	.025 to .065 inch.
Material of fire ring segments	Similar to S.A.E-1070 hardened and tempered

The above described piston and fire ring construction of the present invention has been found through actual field experience to greatly reduce the problems of top ring sticking and bore scuffing, particularly in heavy duty diesel engines. The fire rings of the invention appreciably reduce carbon deposits on the head land of the piston and in the top compression ring groove to thereby enable an internal combustion engine to operate for a considerably longer period even at wide open throttle without stickin of either the compression or the fire rings. It is to be understood that the piston and fire ring construction disclosed herein may also be applied in accordance with the present invention to diesel engines other than the open chamber type as well as to gasoline or gas engines if the above mentioned problems are being encountered.

We claim:

1. In combination: a piston adapted for reciprocation in an internal combustion engine cylinder, said piston having a transverse end surface adapted to form a movable wall of the cylinder combustion chamber, a cylindrical peripheral surface having a plurality of circumferential grooves therein spaced axially from one another and from said end surface including first and second grooves respectively constituting the closest and next closest grooves to said end surface of said plurality of grooves, and a head land bounded by said end surface and said second groove; a set of piston rings individually disposed in all but said first groove of said plurality of grooves including

a parted first compression ring disposed in said second groove having a free state outside diameter greater than the diameter of the cylinder whereby said compression ring is adapted to be radially compressed by the cylinder wall to develop compression sealing contact therewith; and a parted fire ring disposed in said first groove and constituting the sole ring element disposed in said first groove, said fire ring being dimensioned axially relative to said first groove to provide a predetermined axial clearance therebetween sufficient to permit said fire ring to dish and move axially in said first groove in response to piston reciprocation in the cylinder, said fire ring having a free state inside diameter greater than the root diameter of said first groove to permit rotation of said fire ring relative to the piston in response to piston reciprocation and said fire ring having a free state outside diameter substantially equal to the diameter of the cylinder such that said fire ring has a relatively low unit pressure contact with the cylinder wall compared to that of said first compression ring whereby said fire ring has a mere wiping rather than sealing contact with the cylinder wall.

2. The combination set forth in claim 1 wherein said axial clearance between said fire ring and said first groove is greater than the axial clearance provided between said compression ring and said second groove.

3. The combination set forth in claim 1 wherein said axial clearance between said fire ring and said first groove falls within a range from about .003 to .012 inch.

4. The combination set forth in claim 1 wherein said axial clearance between said fire ring and said first groove falls within a range from about .003 to .006 inch.

5. In combination: a piston adapted for reciprocation in an internal combustion engine cylinder, said piston having a transverse end surface adapted to form a movable wall of the cylinder combustion chamber, a cylindrical peripheral surface having a plurality of circumferential grooves therein spaced axially from one another and from said end surface including first and second grooves respectively constituting the closest and next closest grooves to said end surface of said plurality of grooves, and a head land bounded by said end surface and said

second groove; a set of piston rings individually disposed in all but said first groove of said plurality of grooves including a parted first compression ring disposed in said second groove having a free state outside diameter greater than the diameter of the cylinder whereby said compression ring is adapted to be radially compressed by the cylinder wall to develop compression sealing contact therewith; and a plurality of parted fire rings disposed in said first groove and constituting the sole ring elements disposed in said first groove, said fire rings each being dimensioned axially relative to one another and to said first groove to provide a predetermined axial clearance between the combined axial dimension of said fire rings and the axial dimension of said first groove sufficient to permit said fire rings to dish and move axially in said first groove in response to piston reciprocation in the cylinder, said fire rings each having a free state inside diameter greater than the root diameter of said first groove to permit rotation of said fire rings relative to the piston in response to piston reciprocation, said fire rings each having a free state outside diameter substantially equal to the diameter of the cylinder such that said fire rings each have a relatively low unit pressure contact with the cylinder wall compared to that of said first compression ring whereby said fire rings each have a mere wiping rather than sealing contact with the cylinder wall.
